UNITED STATES PATENT OFFICE.

PERCIVAL W. JONES, OF WARWICK, RHODE ISLAND, ASSIGNOR TO ROSENHEIM CO. INC., OF PROVIDENCE, RHODE ISLAND, A CORPORATION OF RHODE ISLAND.

BRACELET CLASP.

Application filed June 24, 1927. Serial No. 201,124.

This invention relates to a clasp of the type more especially designed for the holding together of two ends of a bracelet of the metal band type; and the object of this invention is the provision of a construction whereby the ends of the bracelet overlie each other and are forced into firm engagement with each other to prevent separation thereof.

A further object of the invention is the provision of a clasp having a body which is attached to one of the ends of the bracelet band with the band end spaced from a portion of the body to receive between it and the body the opposite end of the band with means for forcing both the ends together to prevent separation thereof.

This invention further consists in the provision of a clasp having a body secured to one end of the bracelet band and a pivotally mounted cam for forcing the free end of the bracelet band into engagement with the body of the clasp to prevent separation of the parts.

With these and other objects in view, the invention consists of certain novel features of construction, as will be more fully described, and particularly pointed out in the appended claims.

In the accompanying drawings:

Figure 1 is a side elevation illustrating a band bracelet as attached to a wrist watch with the clasp in working position.

Figure 2 is a perspective view showing the clasp in its gripping position for retaining the opposite ends of the bracelet against separation.

Figure 3 is a central sectional view of the clasp shown in relation to the band ends in separated position.

Figure 4 is a sectional view on substantially line 4—4 of Figure 2.

Figure 5 is a sectional view on substantially line 5—5 of Figure 3.

Figure 6 is a section on line 6—6 of Figure 4.

Figure 7 is a sectional view on line 7—7 of Figure 4.

Figure 8 is a perspective view of the clasp with its gripping cam removed and showing the same detached from the bracelet band.

Figure 9 is a perspective view showing the relative position of the different plates of the clasp with the securing arms folded about the band end to hold the same in position.

Figure 10 is a perspective view of the cam

member for forcing the ends into locked position.

Figure 11 is a perspective view of the band end showing an opening therein to receive the fingers on the embracing arms of the 60 clasp to firmly secure the same thereto.

It is found in practice in the securing of a wrist watch in position, desirable to provide a flat metal band to encircle the wrist, which shall be smooth and cool in hot 65 weather and comfortable on the wrist, and in order to provide a clasp for the ends of this type of band which may be easily manipulated for adjusting or securing the band to the wrist of the different users and for 70 quick and easy detachability, I have provided a body so shaped as to receive both ends of the band with means including a cam member for forcing the ends of the band into firm contact to prevent a separation of 75 the same and which may be easily manually manipulated to permit adjustment or detachability when desired; and the following is a detailed description of the present embodiment of this invention illustrating one 80 means by which these advantageous results may be accomplished:—

With reference to the drawings, 10 designates a wrist watch having band parts 11 and 12 secured thereto by means of suitable 85 hooks 13 engaging the bails or lugs of a wrist watch, the end portions 14 and 15 of these band parts overlying one another and are secured together by means of a clasp having a body portion 16 which has at one 90 end arms 17 folded about the end portion 15 of the band with fingers 18 extending into an opening 19 in the band to embrace this end portion and securely lock the body thereto against separation or a sliding movement, the end 20 of this portion 15 extends beyond the embracing arms 17 and is spaced from the anvil plate 21, as illustrated in Figure 3, to leave a gap 22 for the reception of the opposite end 14 of the band. Ears 100 23 are provided on the opposite sides of the anvil plate and extend upwardly therefrom and pivotally mounted in openings 26 in these ears there is a cam member 24 having a cam surface 25 in contact with the band end 20, which member when rotated on its pivot causes the band end 20 to be forced against the opposite end 14 and both ends toward the anvil plate 21 to firmly secure the two ends together against separation. 110

By causing the cam member 24 to act through the band end 20 an enlarged surface or frictional contact is secured between the opposite band ends than if merely the ear portions 27 of the cam member were caused to directly contact with the end 14.

It will be apparent from the foregoing that I have provided a clasp which is simple in construction and yet one which permits 10 easy and quick adjustability and detachability of the bracelet and one which is so constructed that it is durable in operation and yet is of the minimum bulk to present a neat appearance to avoid the undesirability 15 of clumsiness.

The foregoing description is directed solely towards the construction illustrated, but I desire it to be understood that I reserve the privilege of resorting to all the mechanical 20 changes to which the device is susceptible, the invention being defined and limited only by the terms of the appended claims.

I claim:

1. A band clasp comprising a body having 25 arms to receive and secure between them and the body one end of the band and an anvil plate spaced from said band end to receive between it and the said band end the opposite end of the band, and means for forcing both of said ends toward said anvil plate.

2. A band clasp comprising a body having arms to receive and secure between them and the body one end of the band and an 30 anvil plate spaced from said band end to receive between it and the said band end the opposite end of the band, and a cam member pivotally mounted in said body for forcing both of said ends toward said anvil plate.

3. In combination with a band bracelet, a clasp having a body, arms on the sides of 40 said body to embrace one end portion of the bracelet band to secure it thereto with the end of the band extending beyond said arms, an anvil plate spaced from the band end to receive between it and the anvil plate the opposite end of the bracelet, ears on said anvil plate, and a cam member pivoted in

said ears in contact with the extending band 50 end for forcing it and the opposite end toward the anvil plate to prevent separation of the said ends.

4. In combination with a metal band bracelet having an opening in one end portion, a clasp having a body to receive the end having said opening, arms on said body to embrace said end portion, fingers on said arms to extend into said opening to secure the end to the body, the end of said band 55 having a portion extending beyond said arms, an anvil plate spaced from the extending band end to receive between it and the anvil plate the opposite end of the bracelet, ears on said anvil plate, and a cam member pivoted in said ears in contact with the extending band end for forcing it and the opposite end toward the anvil plate to prevent separation of said ends.

5. A band clasp comprising a body, a 70 band in said body, means for permanently securing one end portion of the band to said body at a point removed from the extremity of said band leaving a portion of the band 75 extending in the same direction beyond said securing means, a portion of the body being offset from said securing means to provide a space between it and the extending portion of said band end for receiving the other end of the band, and means positioned to engage the extending end portion to force it toward said offset portion and clamp the ends of the band in the body.

6. A band clasp comprising a body, a band 80 in said body, means permanently securing 85 one end portion of the band to said body at a point removed from the extremity of said band leaving a portion of the band extending in the same direction beyond said securing means, a part of said body being 90 spaced from the extending portion of the band for receiving the opposite end of the band, and means for engaging the extending band end and binding the received portion between said extending band end and the 95 body.

In testimony whereof I affix my signature.
PERCIVAL W. JONES.
